UNITED STATES PATENT OFFICE.

CLEMENT F. STREET, OF GREENWICH, CONNECTICUT.

LOCOMOTIVE STACK.

Application filed April 4, 1925. Serial No. 20,623.

To all whom it may concern:

Be it known that I, CLEMENT F. STREET, a citizen of the United States, and a resident of Greenwich, in the county of Fairfield and State of Connecticut, have invented a certain new and useful Improvement in Locomotive Stacks, of which improvement the following is a specification.

My invention relates to smoke stacks for locomotive engines, and is an improvement upon that for which Letters Patent of the United States No. 1,239,370, were granted and issued to William Elmer, under date of September 4, 1917. The object of my invention is to provide means, of simple and inexpensive construction, whereby the members of a multiple smoke stack, of the type set forth in said Letters Patent No. 1,239,370, may be accurately assembled, and securely maintained, in proper relation, and means for supporting a smoke stack, of such type, in operative position, with the capacity of ready removal and replacement, when desired, and without interfering with the location of adjacent members in the locomotive smoke box.

The improvement claimed is hereinafter fully set forth.

In the accompanying drawings: Figure 1 is a vertical central section through a locomotive stack embodying my invention, located in operative position in connection with the smoke box of a locomotive boiler; and Figs. 2 and 3, horizontal sections 35 through the same, on the lines *x-x* and *y-y*, respectively, of Fig. 1.

In the practice of my invention, referring descriptively to the specific embodiment thereof which is herein exemplified, the multiple smoke stack comprises a plurality of discharge channels, 1, which are disposed, in vertical planes, symmetrically about its axial line. The discharge channels, which are preferably wrought metal tubes, are assembled in proper relative positions, by being inserted, at their ends, in guiding lugs in an upper head plate, 2, and a lower head plate, 2^a, said guiding lugs being formed at the inner ends of openings in the head plates, which openings are of the same diameter, in the upper head plate, as that of the inside of the discharge channels, and are preferably, as shown, outwardly flared or tapered, in the lower head plate. When so assembled, the discharge channels and the

head plates are connected, with the capacity of ready attachment and replacement, when desired, by longitudinal bolts, 3, passing through the head plates, and having heads, 3^a, bearing on one of said plates, and nuts, 3^b, engaging screw threads at their opposite ends and bearing on the other plate. The connection of the discharge channels to the head plates, may, if preferred, be made by welding.

The completed stack is fitted in a concentric outer casing, 4, connected to the smoke box, 5, of the boiler, in line axially with the exhaust pipe, 6, the exhaust steam from which is discharged through a plurality of nozzles, 6^a, corresponding in number and in relative axial relation with the discharge channels, 1. A packing ring, 7, is shown in Fig. 1, as fitted in the upper head plate, 2, to prevent the down rush of air into the smoke box, through the spaces between the discharge channels and the casing, 4, due to the vacuum in the smoke box.

It is of importance, in operation, that each of the discharge channel openings of the lower head plate, 2^a, shall be, at all times, directly in line axially over one of the exhaust pipe nozzles, 6^a, and that said openings and nozzles shall have fixed positions, relatively one to the other. To this end provision must be made for variations in workmanship, in fitting the parts, as well as for expansion and contraction under variations of temperature, and this may be accomplished, under my invention, by the construction herein exemplified, referring more particularly to Fig. 1.

The exhaust pipe, 6, passes through the table plate, 8, connected to the diaphragm, 9, in the usual manner, and a sheet of netting, 10, extends upwardly and forwardly from the table plate to the wall of the smoke box. The discharge of steam from the exhaust pipe is effected, through a plurality of nozzles, 6^a, formed integral with connecting ribs, 6^b, and bolted to the exhaust pipe, each of said nozzles, standing in line axially with one of the discharge channels, 1, of the stack.

As shown in Fig. 1, the stack is firmly supported, independently of a direct connection with the smoke box, and with the capacity of ready attachment and removal, as desired, without interference with the ready removal of the nozzles independently of the supporting bolts, by a plurality of vertical

bolts, 11, the ends of which are threaded, said bolts passing through lugs on the lower head plate, 2^a, and on the exhaust pipe, 6, respectively, and having nuts, 4^a, which engage their threaded ends and bear on the head plate and on the exhaust pipe. Instead of such threaded connection, keys, passing through the bolts, and bearing on the head plate and exhaust pipe, may, if preferred, be applied.

The structural features of my invention above described, enable the operative advantages of that of Patent No. 1,239,870 to be made effectually available, with a minimum of cost of installation and of liability to breakage or derangement in operation.

I claim as my invention and desire to secure by Letters Patent:

1. In a multiple locomotive stack, the combination of a plurality of vertical discharge channels; and head plates, to which said discharge channels are fitted and maintained in normal relative positions.

2. In a multiple locomotive stack, the combination of a plurality of vertical discharge channels; head plates to which the ends of said passages are fitted; and longitudinal bolts, passing through said head plates and connecting them with the interposed channels.

3. In a multiple locomotive stack, the combination of a plurality of vertical discharge channels; an upper head plate, to which the upper ends of said discharge channels are fitted; and a lower head plate, having outwardly flared or tapering openings, to which the lower ends of the discharge channels are fitted.

4. In a multiple locomotive stack, the combination of a plurality of vertical discharge channels; upper and lower head plates, fitted to the ends of said channels; and a casing, enclosing said upper head plate and the adjacent portions of the discharge channels and connected to a locomotive smoke box.

5. In a multiple locomotive stack, the

combination of a plurality of vertical discharge channels; upper and lower head plates, fitted to the ends of said channels; and a casing, in which the upper head plate is fitted without positive connection, and which is connected to a locomotive smoke box.

6. The combination, with a locomotive smoke box, of a multiple locomotive stack; an exhaust pipe, located below said stack; and means for connecting said stack to the exhaust pipe.

7. The combination, with a locomotive smoke box, of a multiple locomotive stack, comprising a plurality of vertical discharge channels; fitted to upper and lower head plates; an exhaust pipe, located below the stack; and means for supporting the stack on the exhaust pipe.

8. The combination, with a locomotive smoke box, of a multiple locomotive stack, comprising a plurality of vertical discharge channels; an exhaust pipe located below the stack; means for supporting the stack on the exhaust pipe; and a casing, connected to the smoke box, and maintaining the stack in line with the exhaust pipe.

9. In a multiple locomotive stack, the combination of a plurality of vertical discharge channels; upper and lower head plates, fitted to the ends of said channels; a casing, enclosing said upper head plate and the adjacent portions of the discharge passages, and connected to a locomotive smoke box; and means for preventing the ingress of air between the upper head plate and the casing.

10. The combination, with a locomotive smoke box, of a multiple locomotive stack, comprising a plurality of vertical discharge channels, fitted, at their ends, to upper and lower head plates; an exhaust pipe, located below the stack, in line axially therewith; and bolts, connected detachably to the lower head plate and to the exhaust pipe, and supporting the stack on the exhaust pipe.

CLEMENT F. STREET.
